UNITED STATES PATENT OFFICE.

EDWARD POSSON, OF CHICAGO, ILLINOIS.

COLUMN-CASTING FOR RAILWAY-CARS.

1,369,906.

Specification of Letters Patent.

Patented Mar. 1, 1921.

Application filed December 22, 1919. Serial No. 346,650.

To all whom it may concern:

Be it known that I, EDWARD POSSON, a citizen of the United States, residing at Chicago, in the county of Cook and State of Illinois, have invented certain new and useful Improvements in Column-Castings for Railway-Cars, of which the following is a specification.

This invention relates to improvements in car trucks, and particularly in the column castings embodied in the side frames of car trucks.

In railway car trucks as usually constructed particularly in the trucks of freight cars, the side frames consist of upper and lower arch bars having vertical column castings extending between them. The truck bolster and associated mechanisms enter the space between the column castings of each side frame, and when the springs of the truck are compressed there is considerable vertical movement of the ends of the bolster and the spring caps with respect to the column castings. This movement causes relatively rapid wear of the inner faces of the column castings, and makes it necessary to replace the entire castings after they have become worn.

The principal object of the present invention is to provide a column casting having a removable wearing portion adapted to coact with the truck bolster, or other movable parts of the structure adjacent thereto. A further object of the invention is to provide a column casting having a removable wearing portion which is held in position by the bolts which secure the column castings to the arch bars. Still another object is to provide a wear plate which may be readily replaced when worn, without the necessity of replacing the entire column casting. Other objects relate to various features of construction and arrangement which will be pointed out more clearly hereinafter.

The nature of the invention will be understood from the following specification, taken in connection with the accompanying drawings, in which one embodiment is illustrated.

In the drawings—

Figure 1 shows a side elevation of a car truck embodying the invention;

Fig. 2 shows a top plan view of one side of the car truck;

Fig. 3 shows an enlarged, vertical section

through the column castings, taken on the line 3—3 of Fig. 2;

Fig. 4 shows a transverse sectional view, taken on the line 4—4 of Fig. 1;

Fig. 5 shows a perspective view of one of the removable wear plates;

Fig. 6 shows a perspective view of one of the column castings, looking toward the inner side thereof, which receives the removable plate; and

Fig. 7 shows a perspective view of the rear or outer side of the column casting.

The invention is shown as applied to a car truck comprising the usual flanged wheels 10 mounted on the axles 11, upon which the journal boxes 12 are supported. These journal boxes support the upper and lower arch bars 14 and 15, respectively, which coact with each other at their ends and are seated upon the upper surfaces of the journal boxes, thus forming a substantially diamond shaped frame. Each side frame also comprises an auxiliary arch bar 16, which underlies the arch bar 15 and extends beneath the underside of the journal box. The arch bars are secured to the flanges 17 of the journal boxes by means of bolts 18 and nuts 19.

The central spaced apart portions of the upper and lower arch bars are adapted to receive between them, the vertically extending column castings 20 which are of the form illustrated particularly in Figs. 6 and 7. Each column casting 20 comprises an upper wall or plate 21, a lower wall or plate 22, integral side walls 23 and an integral forward wall or inner face 24. Integral flanges 25 extending downwardly from the lower wall 22 are adapted to pass on opposite sides of the lower arch bar 15 and auxiliary arch bar 16. Laterally extending ears or brackets 26 are formed on opposite sides of the side columns and on the outer sides of the flanges 25, these brackets being united to the lower ends of the side walls 23 by means of horizontal webs 27. These brackets are provided with apertures 28 adapted to receive rivets 29 by which the lower spring seats or supports 30 are carried. On the inner side of each column casting, there is formed a brake hanger bracket 33. This bracket comprises two hub portions 33^a which are apertured to receive the hanger pins 34 from which the brake hangers 35

are suspended. The brake shoes 36 are carried by the hangers 35. Each hanger bracket 33 is reinforced between the hub portions 33^a and 33^b and the hanger brackets are 5 further reinforced by ribs 37 and 38 which unite them to the inner side walls 23 of the column castings. The side walls 23 of the brackets extend upwardly beyond the upper walls 21, forming flanges or lips 29 which 10 are adapted to extend upwardly on opposite sides of the upper arch bar 14.

Each column casting 20 also comprises a vertically extending post or body portion 40 which is formed integrally with the upper 15 and lower walls 21 and 22, respectively, and with the forward wall 24. Each post is provided with vertical apertures 41 adapted to be engaged by the bolts 42 which extend through the arch bars and through the column castings, being engaged at their lower 20 ends by the nuts 43, whereby the central parts of the side frame are secured in assembled relation.

The forward face 24 of each column casting is offset inwardly or cut away to form a recess 44 and the central part of the cut-away portion is provided with a pocket 45 which is formed in the central enlarged portion 40^a of the post 40. The apertures 41 25 communicate with this pocket and the portion of the bolt 42 passing through the pocket is adapted to engage an apertured lug or boss 46 formed on the inner side of a removable wear plate 47. The wear plate is 30 adapted to enter the cut away portion 44 of the column casting between the upper and lower shoulders 48 and 49, respectively, and the engagement of the bolt 42 with the lug 46 serves to secure the wear plate in position. The spring seat 30 supports the usual 35 coil springs 50 which are engaged at their upper ends by the spring cap 51 having ears 51^a adapted to pass on opposite sides of the side columns 20. The upper spring seat 51 supports one end of the body bolster 53, which bolster is provided at its end with ears 54 adapted to extend beyond the inner 40 faces of the column castings.

During the operation of the car, the 45 springs 50 are compressed and expanded frequently, causing a corresponding vertical movement of the bolster 53 and spring cap 51 with respect to the column castings 20. The wear occasioned by this movement is 50 received by the removable wear plates 47 so that after continued use of the car, the wear plates 47 may be replaced by new ones

thus restoring the structure of the side frame without the necessity of replacing the entire column castings. 60

Although I have shown and described one form of the invention for purposes of illustration, it will be understood that it may be constructed in various other forms without departing from the scope of the appended 65 claims.

I claim:

1. The combination in the side frame of a railway truck of upper and lower arch bars, column castings spaced apart and extending 70 between said arch bars, removable wearing plates engaging said column castings, and a single means for securing said wearing plates and said upper and lower arch bars to said column castings. 75

2. The combination in the side frame of a railway truck of upper and lower arch bars, column castings spaced apart and extending between said arch bars, removable wearing plates engaging said column castings, and 80 bolts extending downwardly through both of said arch bars and said column castings and extending through parts of said wearing plates. 85

3. The combination in the side frame of a railway truck of upper and lower arch bars, column castings extending between said arch bars, a bolster projecting between said column castings, wearing plates mounted on the opposite faces of said column castings to 90 coat with said bolster, said column castings being provided with recesses, said wearing plates having parts engaging said recesses, and bolts extending downwardly through both of said arch bars and said column castings and engaging the parts of said wearing plates which pass through said recesses. 95

4. The combination in the side column of a railway truck, of side walls united by an inner wall, upper and lower walls uniting 100 said inner wall with said side walls, a vertical post formed integrally with the rear side of said inner wall and extending between said upper and lower walls, said inner wall being provided with a recess extending 105 inwardly into said post, said post being provided with apertures extending into said recess, a wearing plate having an apertured part engaging said recess, and a bolt extending through said apertures to secure said 110 wearing plate in position.

In testimony whereof, I have subscribed my name.

EDWARD POSSON.
